UNITED STATES PATENT OFFICE

2,686,325

TOOTHBRUSH

Louis Silver, Brooklyn, N. Y.

Application March 17, 1950, Serial No. 150,297

1 Claim. (Cl. 15—188)

1

This invention relates to toothbrushes and more particularly to toothbrushes which are in the form of finger sleeves adapted to be slid over a finger and which depend on finger motion for their cleansing action.

It is an object of this invention to provide a finger sleeve toothbrush which affords a thorough cleansing action on all exposed parts of the teeth and gums as well as the areas between the teeth and the gums, while preventing any rough or harsh action on said teeth or gums, such as may be caused by the use of a bristle type toothbrush.

It is also an object of this invention to provide a finger sleeve toothbrush which has maximum maneuverability and maintains a uniform and constant pressure for teeth cleaning and gum massaging.

Additionally it is an object of this invention to provide a finger sleeve toothbrush which covers substantially the entire length of the finger so as to maintain the desired sanitary protection for the user.

It is also an object of this invention to provide a finger sleeve toothbrush whose facility of use and efficiency are not impaired by long or protruding fingernails.

It is also an object of this invention to provide a finger sleeve toothbrush which may readily be put on and pulled off and which at the same time will remain steadfast when on the finger and in use.

Further this invention sets forth a finger sleeve toothbrush which by virtue of its onepiece construction gives maximum service and wearability so as to be both economical, durable, and readily manufactured in large scale production.

Further and more particular objects of this invention will appear from the following description, read in the light of the accompanying drawings, of which

Figure 1 is a cross-sectional side view of the finger sleeve toothbrush showing the ridges on the undersurface of the finger sleeve and the projection on the closed end thereof;

Figure 2 is a bottom plan view of the finger sleeve toothbrush showing the ridges and projection on the finger sleeve as well as the tab formed on the open end thereof;

Figure 3 is a cross-sectional side view of the finger sleeve toothbrush showing a finger inserted therein;

Figures 4, 5 and 6 are views similar to Figure 2 showing variations in the type of ridges which may be provided on the finger sleeve.

As shown in Figure 1, the toothbrush, which is

2

wholly made of a resilient rubber-like material, is formed of a finger sleeve 1 having a closed end 2 and an open end 3, and adapted to fit over substantially the entire length of a finger. Adjacent 5 the closed end section, at its undersurface (this designation may be taken, for the purpose of this description, to mean that part of the finger sleeve which coincides with the undersurface of the finger when positioned in the sleeve as opposed to 10 the top surface containing the fingernail), the sleeve is provided with transverse ridges 4 (see also Figure 2). The ridges 4 are bordered with a series of shorter ridges 6, the apices of the ridges 6 being at substantially right angles to 15 those of ridges 4 and extending outwardly thereof. The closed end 2 is provided with a pointed projection 5.

In use, the finger is slipped into the sleeve 1 at the open end 3 and the finger is positioned in the 20 sleeve by use of a pulling action on tabs 7 and 8 (see Figure 1), which are provided at the open end 3 of the sleeve 1.

The sleeve is tapered at its closed end, as shown in Figures 1 and 3, and is of such length that a 25 finger having a long and protruding fingernail, such as is common with women, is suitably permitted to be retained in the sleeve without breaking the fingernail or having it dig into the sleeve, resulting in tearage, and the finger is substantially 30 fully covered so as to prevent contact between the finger and the mouth of the user, thus preserving the desired sanitary conditions in using this toothbrush.

The transverse ridges 4 on the undersurface of 35 the sleeve 1 are suitably pyramidal in shape as shown in Figure 2. Likewise they may be of diagonal, zigzag, or rectangular, diagonal and sinusoidal as shown in Figures 4, 5 and 6. Since they are made of a resilient rubber-like material, when the ridges are moved against the teeth and 40 gums, there results a squeegee action which thoroughly cleans the whole tooth and gum area, in contrast to the action attained by the bristle type toothbrush in common use.

The shorter ridges 6, bordering the transverse 45 ridges 4 serve to effectively clean the junction area of the gums and teeth by a meshing type of action. The pointed projection 5, by virtue of its shape, serves to clean between-the-teeth areas 50 by effectively projecting into these narrow spaces.

The ridges 4 and 6 may be effectively located on a thickened portion of the sleeve 10, as shown in Figure 1. The thickened portion 10 is located on the undersurface of that part of the sleeve 55 which corresponds to the outermost joint of the

finger which is to be inserted, which is normally the first finger on the hand. By so locating the thickened portion with ridges and projection in this section, there is attained maximum movement and even pressure on all parts of the teeth and gums during cleaning.

Either upper tab 7 or lower tab 8 (or both), may be provided with a hole 9 for hanging the toothbrush when not in use. The lower tab 8 is slightly longer than the upper tab and is conveniently equipped with several cross ridges or a roughened surface preferably on both sides, which is adapted to be retained by the thumb, thus preventing the sleeve from being pulled off in the cleansing and massaging process.

A drainage hole 12 is provided at the top surface at the closed end section of the finger sleeve as shown in Figure 1 so as to permit any liquid which has collected in the toothbrush to flow out. In addition, this hole serves to permit egress of air from the finger sleeve when the same is placed upon the finger.

Although I have described a preferred embodiment of this invention, I do not wish to be limited by the foregoing description but solely by the claim granted me.

What is claimed is:

A flexible finger sleeve toothbrush made of a resilient material comprising a finger sleeve, closed at one end and open at the other, said finger sleeve

being adapted to fit over substantially the entire length of a finger, and having a thickened section at its outer surface with a plurality of ridges thereon, said ridges being located at that section of the sleeve coincident with the underside of the outermost joint of a finger when inserted in said sleeve, and comprising one set of ridges running substantially transverse to the length of the sleeve, and another set of ridges bordering the transverse set of ridges, and substantially triangular in shape, the apices thereof being at substantially right angles to the crests of the transverse ridges, said closed end being provided with sufficient space to accommodate a protruding fingernail and having at the tip thereof a pointed projection for between-the-teeth cleaning.
